(57) **CLAIM**

The ornamental design for a hookah table, as shown and described.

DESCRIPTION

FIG. 1 is a top perspective view of a hookah table.

FIG. 2 is a bottom perspective view of the hookah table of FIG. 1.

FIG. 3 is a right side view of the hookah table of FIG. 1, of which the left side view is a mirror image thereof.

FIG. 4 is a front view of the hookah table of FIG. 1, of which the back view is a mirror image thereof.

FIG. 5 is a top view of the hookah table of FIG. 1; and, FIG. 6 is a bottom view of the hookah table of FIG. 1. The broken line showing of elements on the hookah table illustrate portions of the article and form no part of the claimed design.
